PIVOTALLY ADJUSTABLE SPRAY NOZZLE
DEFLECTOR

Thomas J. Weaver, Cream, Utah

Application June 20, 1947, Serial No. 755,925

4 Claims. (Cl. 299—129)

1

This invention relates to a sprayer nozzle for a hose of the type used for watering lawns and it is one object of the invention to provide a nozzle having attached thereto a spike or prong adapted to be forced into the ground and support the nozzle in position for discharging water onto a lawn, the spike or prong carrying a plate mounted in such position that water discharged from the nozzle will strike the plate and be formed into a spray.

An other object of the invention is to provide a nozzle of this character wherein the spray-forming plate is provided with a shank extending rearwardly from the plate and pivoted to the spike so that the plate may be tilted to angularly adjusted positions and thus control the form of the spray formed by the discharged water.

Another object of the invention is to provide a spray nozzle wherein the shank of the spray-forming plate is pivoted to the supporting spike by a pin carrying an arm which extends diagonally between the nozzle and the rear portion of the shank and has movement toward and away from the rear edge of the spike as the pin is slid longitudinally through the spike and the shank, the arm thus sliding along the upper edge of the shank and creating a cam action which causes the spray plate to be tilted vertically and prevented from being forced downwardly by action of a stream of water discharged from the nozzle and striking the upper face of the plate.

Another object of the invention is to provide a spray nozzle having a spraying plate pivoted to a supporting spike for the nozzle and moved to an angularly adjusted position by an arm carried by a pivot pin for the plate, the said arm carrying a finger which prevents entire displacement of the pin and thus prevents the plate from becoming detached from the spike.

Another object of the invention is to provide a spray plate so formed that a spray will cover a relatively large area of lawn.

Another object of the invention is to provide a spray nozzle which is simple in construction and capable of being applied to a terminal coupling for a hose of conventional form.

The invention is illustrated in the accompanying drawings wherein:

Fig. 1 is a side view showing the improved spray nozzle in use.

2

Fig. 2 is a front view of the improved spray nozzle.

Fig. 3 is a rear view of the nozzle.

Fig. 4 is a view taken along the line 4—4 of Figure 1 and showing the nozzle in bottom plan and its spike in transverse section.

Fig. 5 is a sectional view taken longitudinally of the nozzle along the line 5—5 of Figure 2.

Fig. 6 is a side view showing the spray plate tilted to an adjusted position.

This improved spray nozzle has a nozzle 1 formed of cast metal and internally threaded, as shown in Figure 5, so that it may be screwed upon the threaded terminal coupling 2 of a hose 3. The usual rubber gasket or washer 4 forms a water-tight joint between the nozzle and the coupling 2 and forwardly of this washer the nozzle is tapered and formed with an outlet opening 5 through which a stream of water is discharged from the nozzle. A spike 6 extends downwardly from the forward portion of the nozzle and is of such length that when it is forced into the ground the nozzle will be supported close to the ground in substantially a horizontal position, as shown in Figure 1. By having the spike rectangular in cross section its flat side faces will prevent turning of the shank in the ground and the nozzle will be held in position to discharge water in a predetermined direction.

In order to form a spray of water discharged from the nozzle there has been provided a plate 7 disposed in front of the nozzle and carrying a shank 8 which projects rearwardly from the spray plate. A slot extends longitudinally of the shank from the rear end thereof and forms forks 9 for straddling the spike 6, the forks and the prong being formed with aligned openings through which a pin 10 of stiff metal is passed to serve as a pivot pin and mount the plate for tilting movement vertically to adjusted positions between that shown in Figure 1 and the raised position shown in Figure 6. The forks 9 are of such length that when the pin is passed through them to pivotally mount the spray plate the forks will project rearwardly from the spike and under the rear portion of the socket 1. The strand of wire from which the pivot pin 10 is formed is bent to form an arm 11 extending from the pin in a horizontal plane at a rearward incline under the nozzle transversely thereof,

and upon referring to Figures 1 and 6 it will be seen that when the pin is shifted longitudinally through the forks and the spike by pressure applied to one end of the pin the arm will gradually move towards the spike through space between the forks and the nozzle. The upper edge faces of the forks extend rearwardly at a downward incline and thus provide cam surfaces which bear against the under surface of the arm and cause the shank to be tilted about the pivot pin and swing the spray plate vertically to adjusted positions during longitudinal movement of the pin and the arm. Therefore the spray plate will be tilted vertically from the position shown in Figure 1 toward that shown in Figure 6 and since the stream of water discharged from the nozzle strikes the sloping upper surface of the plate a spray will be formed having characteristics which may be modified by tilting of the plate to adjusted positions. The free end portion of the arm 11 is bent to form a finger 12 which terminates close to the free end of the pivot pin and since this pin overlaps the outer side face of one of the forks 9 longitudinal movement of the pin through the forks and the spike when shifted toward the positions shown in Figure 2 will be limited and the pin can not become displaced from the openings through which it passes. The fact that the arm fits between the forks and the under surface of the nozzle causes a gripping action upon the arm when the forks are tilted upwardly by pressure of water striking the upper surface of the plate and the plate will be firmly held in a set position as the pin and its arm will be prevented from accidentally shifting transversely of the forks and the nozzle.

When this improved spray nozzle is in use the nozzle is screwed upon the terminal coupling 2 of the hose and after the hose has been extended across a lawn a sufficient distance the spike is forced into the ground and as water discharged from the nozzle strikes the spray plate a spray will be formed which moves forwardly from the plate. If it is found that a spray of the desired form is not formed by the plate it is merely necessary to apply pressure to an end of the pin and force the pin longitudinally through the shank and the spike. This causes the diagonally extending arm to move transversely of the forks and as it is shifted longitudinally across the forks it will also move diagonally thereof and impart tilting movement to the shank to raise or lower the plate according to the direction in which the pivot pin and the arm are moved. The finger 12 not only serves to limit longitudinal movement of the pin but also serves as a member against which a thumb or finger may be placed when shifting the pin towards the position shown in Figure 4.

Having thus described the invention, what is claimed is:

1. A sprayer nozzle comprising a nozzle open at its rear and adapted for application to a hose, said nozzle having its front end formed with an outlet opening, a member secured to the forward portion of said nozzle, a sprayer plate in front of the nozzle having a rearwardly extending shank slotted from its rear end to form forks straddling the said member, said shank being formed with openings registering with an opening formed through the said member, a pivot pin passing through the registering opening and pivotally mounting the shank for vertical swinging movement of the plate to angularly adjusted

positions, said forks having their rear portions projecting rearwardly from the said member under the rear portion of the nozzle, and an arm extending diagonally from one end of said pin at a rearward incline in a horizontal plane back of the said member and transversely of the said member between rear portions of the nozzle and the forks and having wedging movement between upper edges of the forks and the nozzle to tilt the shank and move the plate vertically to angularly adjusted positions relative to the outlet opening as the pin is slid longitudinally through the forks and the said member, said arm having its free end portion provided with a forwardly extending finger for engaging the outer side face of a fork and preventing displacement of the pin from the registering openings of the forks and the said member.

2. A sprayer nozzle comprising a nozzle adapted to be applied to a hose and having an outlet opening at its front end, a member secured to and extending downwardly from said nozzle, a sprayer plate in front of the nozzle having a shank extending rearwardly therefrom and formed with forks straddling said member with portions projecting rearwardly therefrom under a rear portion of the nozzle, a pin passing through registering openings formed in the forks and said member and pivotally mounting the shank for vertical swinging movement of the plate to angularly adjusted positions across the outlet opening of the nozzle, and an arm extending horizontally at a rearward angle from one end of the pin between rear portions of the nozzle and the forks and having movement along upper edge faces of the forks to tilt the shank vertically and angularly adjust the plate as the pin is shifted longitudinally through the openings in the forks and the spike.

3. A sprayer nozzle comprising a nozzle adapted to be applied to a hose and having an outlet opening at its front end, a member secured to and extending downwardly from said nozzle, a sprayer plate in front of the nozzle having a shank extending rearwardly therefrom with a portion projecting rearwardly from said member under a rear portion of the nozzle, a pin passing through registering openings in the shank and the said member and pivotally mounting the shank for vertical movement of the plate to angularly adjusted positions in front of the outlet opening, said pin being slidable longitudinally in a direction transversely of the shank and carrying an arm extending diagonally between the shank and the nozzle at a rearward angle between rear portions of the nozzle and the shank, said arm having movement across the shank and longitudinally of the shank to tilt the shank when the pin is shifted longitudinally and hold the plate in an angularly adjusted position.

4. A sprayer nozzle comprising a nozzle adapted to be applied to a hose and having an outlet opening at its front end, a member extending downwardly from said nozzle, a sprayer plate in front of the nozzle having a shank extending rearwardly therefrom and across said member with a portion projecting rearwardly from the said member under a rear portion of the nozzle, a pin passing through the shank and said member and pivotally mounting the shank for vertical movement of the plate to angularly adjusted positions in front of the outlet opening, said pin being slidable through the shank and the said member transversely thereof, and an adjusting member associated with said pin and extending

through space between the shank and the nozzle transversely thereof at a rearward angle, said adjusting member being movable with the pin and during such movement being moved across the shank and also longitudinally thereof for tilting the shank and thereby moving the plate to angularly adjusted positions.
